DESIGN FOR A SPECTACLE BRIDGE

Herbert Clements, Geneva, N. Y.

Application April 22, 1935, Serial No. 56,516

Term of patent 7 years

To all whom it may concern:

Be it known that I, Herbert Clements, a subject of Great Britain, residing at Geneva, in the county of Ontario and State of New York, have invented a new, original, and ornamental Design for a Spectacle Bridge, of which the following is a specification, reference being had to the accompanying drawing, forming a part thereof.

Figure 1 is a front elevational view of a spectacle bridge embodying my new design.

Figure 2 is a top plan view of the spectacle bridge shown in Figure 1.

Figure 3 is a side elevational view of the spectacle bridge of Figure 1.

I claim:

The ornamental design for a spectacle bridge, substantially as shown.

HERBERT CLEMENTS.
